R. E. ALTOONIAN,
COMBINED WRITING SHEET AND ENVELOPE,
APPLICATION FILED APR. 9, 1918.

1,317,537.

Patented Sept. 30, 1919.

UNITED STATES PATENT OFFICE.

REUBEN E. ALTOONIAN, OF NEW YORK, N. Y.

COMBINED WRITING-SHEET AND ENVELOP.

1,317,537.

Specification of Letters Patent. Patented Sept. 30, 1919.

Application filed April 9, 1918. Serial No. 227,542.

To all whom it may concern:

Be it known that I, REUBEN E. ALTOONIAN, a citizen of the United States, and a resident of New York city, borough of Manhattan, in the county and State of New York, have invented a new and Improved Combined Writing-Sheet and Envelop, of which the following is a full, clear, and exact description.

10 This invention has for its object to provide a combined writing sheet and envelop which is so fashioned that the address used in mailing the envelop will appear on the same side of the writing sheet as the letter, 15 without making use of that portion of the letter sheet which is usually used for the letter.

Another object of the invention is to provide a combined sheet and envelop which 20 may be conveniently folded and sealed.

Additional objects of the invention will appear in the following specification in which the preferred form of my invention is described.

25 In the drawings similar reference characters refer to similar parts in all the views, in which—

Figure 1 is a plan view illustrating my invention;

30 Figs. 2, 3 and 4 are perspective views illustrating the manner in which the combined letter sheet and envelop is folded;

Fig. 5 is a plan view showing the same in folded position; and

35 Fig. 6 is an enlarged transverse sectional view of Fig. 5.

By referring to the drawings, it will be seen that the letter sheet A is preferably oblong and has a margin B at both sides 40 and ends, which is separated from the body of the letter sheet A by perforations C. The margin B at one end of the letter sheet A is coated with an adhesive D, there being indicated on the sheet A, adjacent the 45 said end, a square or inclosure E in which the address of the sendee may be written. At the other end of the letter sheet A, there is a cut-out portion F, through which the 50 address written in the square or inclosure E will be exhibited when the letter sheet A is folded on the transverse line G. To the right of the cut-out portion F, there is a

space H for the letterhead, and to the right of the square or inclosure E, there is a space I for the signature. Extending beyond the 55 margin B above the transverse line G, there is a flap J coated with adhesive.

When a letter is written between the cut-out portion F and the square or inclosure E, and the address of the letter is written 60 in the square or inclosure E, the letter sheet A is folded on the transverse line G and the margins B at the ends of the letter sheet are sealed together by means of the adhesive D. Fig. 2 shows the letter sheet in 65 the process of being folded, at the transverse line G. When the letter sheet has been folded, as described, it is again folded on the longitudinal line K, as illustrated in Fig. 3, and when this has been done the adhesive flap J is secured to the margin B at 70 B'. The sealed letter will then appear as illustrated in Fig. 5.

It will be understood that with the combined sheet and envelop which has been 75 described, the address of the addressee will be preserved on the face of the letter without infringing on the space which is usually used in which to write the letter. It will also be understood that the letter may be 80 thoroughly sealed in the manner which has been described, and that it may be readily opened by tearing off the margins B at the perforations C.

Having thus described my invention, I 85 claim as new and desire to secure by Letters Patent:

A combined letter sheet and envelop adapted to be folded transversely and longitudinally having a margin at its four sides 90 separated from the body of the letter sheet by perforations, the margin at one end of the letter sheet being provided with an adhesive, a flap provided with an adhesive extending beyond the margin at one side 95 of the letter sheet and between the transverse fold and the other end of the letter sheet, the letter sheet having at one end an opening at one side and a letter head at the other side, and at its other end at the 100 first mentioned side an inclosed space for the address and at the second mentioned side a space for signing the letter.

REUBEN E. ALTOONIAN.
